PETER E. GELDHOF, OF SYRACUSE, NEW YORK, ASSIGNOR TO SYRACUSE WASHING MACHINE CORPORATION, OF SYRACUSE, NEW YORK, A CORPORATION OF DELAWARE

FRICITION CLUTCH FOR CONVERTING RECIPROCAL MOTION INTO ROTARY MOTION

Application filed January 19, 1926. Serial No. 82,253.

This invention relates to a friction clutch adapted to be used more particularly in connection with the driving mechanism of a clothes washing machine in which a vertically movable plunger is reciprocated longitudinally by means of a power driven lever hinged to swing about a horizontal axis some distance from its connection with the plunger.

10 In machines of this character the washing mechanism preferably comprises a plurality of inverted cups mounted upon the plunger in circumferentially spaced relation about the axis thereof for vertical movement with-
15 in the tub or vat so as to act upon the clothes by pressure and suction as they are moved downwardly and upwardly and, in order that the cups may act upon practically the entire surface of the clothes, suitable means is pro-
20 vided for intermittently rotating the plunger with the cups thereon or for imparting an intermittent planetary movement to the cups as the plunger approaches the limit of its upward stroke or when the cups are free
25 from engagement with the clothes.

In most machines of this type the plunger extends from beneath upwardly through and above a gland in the bottom of the tub and this gland usually extends some distance
30 above said bottom to afford a proper guide for the plunger in addition to its function of preventing the leakage of water there-
35 through and it frequently happens that when the machine is in operation the intermittent rotary motion causes the clothes to become wound around the center post of the gland resulting sometimes in stopping the opera-
40 tion of the washing mechanism or, when the fabrics are delicate, in mutilation of such

45 Either or both of these results are, of course, objectionable and while I am aware that certain devices have heretofore been used for effecting this intermittent rotary motion with more or less friction drive it has been found that in many of these devices the friction relied upon for imparting the intermittent rotary motion is insufficient under normal conditions while in other machines it
50 is excessive when the clothes become wound

around the center post resulting in more or less mutilation of the clothes as previously explained.

The main object of the present invention is to provide the connection between the power lever and plunger with means for imparting a more positive intermittent rotary motion to the plunger and washing mechanism under normal resistance as the plunger approaches the limit of its upward stroke and at the same time to prevent such intermittent rotation under abnormal resistance such as the winding of the clothes around the plunger or guide post.

I have found that in actual practice this object can be successfully carried out in a most efficient manner by providing the plunger with a concentric peripheral face adapted to be engaged by a circumferentially oscillating friction dog pivotally mounted upon an oscillating member at one side of the axis of the plunger and oscillating said member by the lever as the latter is raised and lowered in the reciprocation of the plunger.

Another object is to provide yielding means for urging the friction dog into engagement with the periphery of the friction disk so as to assure quick action of the pawl upon the disk as the lever and plunger are moved upwardly and also to assure quick release of the disk during the downward movement of the plunger or, in case the clothes should become wound around the plunger or guide post.

Other objects and uses relating to the specific parts of the device will be brought out in the following description.

In the drawings:

Figure 1 is a side elevation of a portion of the plunger and its operating mechanism showing a part of the wash tub or vat in section.

Figure 2 is an enlarged horizontal sectional view taken in the plane of line 2-2.

Figure 3 is an enlarged vertical sectional view taken along the line 3-3, Figure 2.

Figure 4 is a horizontal sectional view taken in the plane of line 4-4, Figure 3.

In order that the invention may be clearly understood I have shown a portion of wash

tub or vat —1— mounted upon a platform —2— of the main supporting frame and provided with a central guide post or gland —3— through which a vertically movable plunger —4— is adapted to be reciprocated.

The washing mechanism, not shown, is adapted to be mounted upon the upper end of the plunger within the vat or tub —1— to act upon the clothes by pressure and suction as the plunger is reciprocated.

The means for reciprocating the plunger comprises a lever —5— having one end pivotally connected to the lower end of a link —5'— which, in turn, is pivoted to the underside of the platform —2— some distance to one side of the plunger —4—.

The inner end of the lever is preferably bifurcated and pivoted to suitable trunnions —6— on diametrically opposite sides of a collar —7—, Figure 3, which, in turn, is loosely mounted upon the lower end of the plunger —4— to permit the latter to turn therein.

The lower end of the collar —7— rests upon an end thrust washer bearing —8— which is held in operative position by a nut —9— engaging the lower threaded end of the plunger —4—, Figure 3, for holding the collar —7— against downward displacement.

The upper end of the collar is engaged by a member —10— which is free to oscillate circumferentially upon the adjacent portion of the plunger —4— and is held against upward displacement by a superposed disk —11— having a peripheral friction surface —11'— concentric with the axis of the plunger, said disk —11— being keyed by pin —12— to the plunger to rotate therewith and also to hold the member —10— and collar —7— against upward displacement on the plunger.

The oscillatory member —10— is provided with laterally projecting arms —10'— and —10''— at opposite sides of its axis, one of said arms as —10'— being provided with a lug —10'''— projecting upwardly across the periphery of the adjacent side of the friction disk —11— for a purpose presently described.

The other arm —10''— of the member —10— is provided with an oil passage —13— leading to the periphery of the plunger —4— for lubricating the bearing surfaces between said plunger and member —10— and incidentally lubricating the bearing between the plunger and collar —7—.

A pawl —14— is interposed between the oscillating member —10— and friction disk —11— and preferably extends entirely around the plunger —4— to form a central opening —15— of appreciably greater diameter than the hub of the member —10— so as to permit the pawl to move laterally relatively to the oscillatory member —10— and friction disk —11—.

One end of the pawl —14— is pivoted at —16— to the arm —10''— of the member

—10— some distance to the corresponding side of the axis of the plunger —4— to permit said pawl to swing laterally.

The other end of the pawl is provided with a friction shoe —17— projecting upwardly across the periphery of the friction disk —11—. Shoe 17 has a rounded front end from which extends outwardly a heel —17'— adjacent one side of the lug —10'''— but in spaced relation thereto to form a bearing for one end of a coiled spring —18— which is seated in a socket —19— in the lug —10'''— as shown in Figure 4.

The side of the inner forked end of the lever —5— adjacent the arm —10''— is provided with longitudinally spaced shoulders —20— and —20'— above the pivot —6— for engaging opposite faces of said arm and thereby imparting an oscillatory motion to the member —10— as the inner end of the lever is rocked upwardly and downwardly for reciprocating the plunger —4—.

The means for operating the lever —5— comprises a power driven shaft —21— journaled in a gear case —22— on the underside of the platform —2— and provided with a crank arm —23— external to said gear case, said crank arm being connected by a pitman —24— to the intermediate portion of the lever whereby the lever will be rocked vertically for imparting a corresponding movement to the plunger —4— as the shaft —21— is rotated.

A compensating arm —25— is journaled at one end on the gear case —22— and has its other end pivotally connected at —26— to the lever —5— to cause the inner end of the lever to move as nearly as possible in a straight vertical line parallel with the plunger.

It will be noted that the inner face of the friction shoe —17— and periphery of the disk —11— are smooth and that the friction face of the shoe is of substantially the same radius as the periphery of the disk —11— and that the spring —18— yieldingly holds the shoe in contact with said periphery under a comparatively light pressure.

It will also be noted that the shoe —17— is located circumferentially mainly to one side of a direct line passing through the pivot —16— and center of the plunger —4— and disk —11— and that the pivot —16— is located at one side of a direct line between the center of the shoe —17— and center of the plunger —4— so that if the arm —10''— of the member —10— is moved toward the left hand, Figures 2 or 4, the pivot —16— for the pawl —14— will be carried with it thereby drawing the shoe —17— radially into frictional engagement with the periphery of the disk —11— for rotating said disk in the direction indicated by arrow —x—, Figure 4.

This movement of the arm —10''— and

5 pivot —16— of the pawl —14— is effected by the shoulder —20'— as the inner end of the lever —5— and plunger —4— approach the limit of their upward strokes or when the washing mechanism is free from engagement with the clothes, during which time the friction shoe —17— will be brought into frictional engagement with the periphery of the disk —11— with sufficient force to rotate the plunger and washing mechanism carried thereby through a relatively small arc of movement by reason of the tendency of the pivot —16— to move toward a direct line 10 passing through the shoe and center of the plunger.

15 *Plunger.* That is, the arm —10"— which moves about the axis of the plunger carrying the pivot —16— with it constitutes what may be termed a crank arm while the pawl —14— serves as a pitman connection between the pivot —16— and shoe —17— so that when the pivot is moved toward a direct line passing through the shoe and center of the plunger it draws the shoe into contact with the periphery of the disk —11— and thereby effects a partial rotation of said plunger and washing mechanism carried thereby as the plunger approaches the limit of its upward stroke.

30 On the other hand as the inner end of the lever —5— and plunger are moved downwardly the lug —20— engages the adjacent face of the arm —10"— thereby rocking said arm toward the right hand of Figure 4 and consequently moving the shoe —17— slightly away from the periphery of the disk —11— ready for a repetition of the intermittent rotary motion as the plunger again approaches the limit of its upward stroke, it being understood that when the arm —10"— is moved in one direction the shoe —17— will be moved in the opposite direction.

The corner of the shoe facing the lug —18— adjacent the disk is slightly rounded as shown in Figure 4 to facilitate the slipping movement of the pawl and friction shoe relatively to the disk in case of abnormal resistance to the rotation of the washing mechanism by the winding of the clothes around the plunger or its guide post or from any other causes.

For example, if, during the upward stroke of the plunger and washing mechanism, the resistance to rotation thereof should be excessive, the shoe —17— will simply ride along the periphery of the disk —11— without rotating the same aided by the rounding corner at the inner end of the shoe.

What I claim is:

60 1. In a friction clutch of the character described, the combination with relatively rotatable co-axial driving and driven members and means for effecting an angular movement of the driving member in reverse directions, of a single friction shoe pivotally

mounted on the driving member and having an angular movement about the axis of the driving member and another movement transversely of said axis for engaging and effecting an intermittent angular movement of the driven member in one direction, said shoe having an outwardly rounding front end, and means actuated by the angular movement of said driving member for effecting both movements of the shoe.

2. In a friction clutch of the character described, the combination with relatively rotatable co-axial driving and driven members and means for effecting an angular movement of the driving member in reverse directions, of a pawl pivoted eccentrically to the driving member to swing transversely of the axis thereof, and a single friction shoe on the pawl having an outwardly rounding front end for engaging the periphery of the driven member, said pivot and shoe being arranged in different radial planes relatively to the axis of rotation of both of said members whereby the angular movement of the driving member in one direction will cause the shoe to frictionally engage and rotate the driven member.

3. In a friction clutch of the character described, the combination with relatively rotatable co-axial driving and driven members and means for effecting an angular movement of the driving member in reverse directions, of a pawl pivoted eccentrically to the driving member to swing transversely of the axis thereof, and a single friction shoe on the pawl having an outwardly rounding front end for engaging the periphery of the driven member, said pivot and shoe being arranged in different radial planes relatively to the axis of rotation of both of said members whereby the angular movement of the driving member in one direction will cause the shoe to frictionally engage and rotate the driven member, and a spring interposed between the shoe and adjacent portion of the driving member for automatically holding the shoe in contact with the periphery of the driven member. 35 100 105 110

In witness whereof I have hereunto set my hand this 8th day of January 1926. 115
